Patented Aug. 3, 1971

221,355

PORTABLE AUTOMATIC RECORD PLAYER OR SIMILAR ARTICLE

Antonio Melandri, Viale Lunigiana 42, Milan, Italy

Filed Nov. 3, 1969, Ser. No. 19,905

Claims priority, application Italy May 2, 1969

Term of patent 14 years

Int. Cl. D14—01

U.S. Cl. D56—4

Fig. 1

FIG. 1 is a top plan view of a portable automatic record player or similar article, showing my new design, the bottom being substantially a mirror image thereof; and

FIG. 2 is a side elevational view, thereof, the opposite side being substantially a mirror image thereof.

I claim:

The ornamental design for a portable automatic record player or similar article, as shown and described.
